CLAIM

The ornamental design for a thermal chamber, as shown and described.

DESCRIPTION

FIG. 1 is an isometric view of a thermal chamber in a closed configuration, showing our new design;
FIG. 2 is a front elevation view thereof;
FIG. 3 is a rear elevation view thereof;
FIG. 4 is a right side elevation view thereof;
FIG. 5 is a left side elevation view thereof;
FIG. 6 is a top elevation view thereof;
FIG. 7 is an isometric view of a thermal chamber in open configuration for clarity of disclosure;
FIG. 8 is a front elevation view thereof;
FIG. 9 is a right side elevation view thereof;
FIG. 10 is a left side elevation view thereof; and,
FIG. 11 is a top elevation view thereof.
The dashed lines shown in the drawings illustrate portions of a wired thermal chamber that form no part of the claimed design.
